OR D 18,818

EX DESIGN.

H. A. SCHNEEKLOTH.

CASE FOR WEIGHING MACHINES.

No. 18,818.

Patented Dec. 18, 1888.

UNITED STATES PATENT OFFICE.

HANS A. SCHNEEKLOTH, OF NEW YORK, N. Y., ASSIGNOR TO THE NATIONAL
WEIGHING MACHINE COMPANY, OF SAME PLACE.

DESIGN FOR A CASE FOR WEIGHING-MACHINES.

SPECIFICATION forming part of Design No. 18,818, dated December 18, 1888.

Application filed October 13, 1888. Serial No. 288,004. Term of patent 7 years.

To all whom it may concern:

Be it known that I, HANS A. SCHNEEKLOTH, of the city, county, and State of New York, have invented and produced a new and original Design for the Case of a Weighing-Machine, of which the following is a specification, reference being had to the accompanying photograph, which represents a perspective view of a weighing-machine of my design.

Upon a base or pedestal, P, is erected a column, A, the horizontal sectional form of which is rectangular. Upon this column is a dial-box, which is of rectangular horizontal section, and which has a square front, and above this box is an entablature, in which are a frieze, j, having a foliated ornamentation, and a cornice, k, of cyma form, having a foliated ornamentation. Above this entablature is a tablet, l, at the sides of which are inverted consoles m. In the front of the column A are three sunken panels, p p', of which the upper and lower ones, p', are smaller than the middle one, p. At the sides of the column are pilasters B, of circular horizontal section, having their bases ornamented by foliated scroll-

work a b, and having their capitals composed, principally, of foliated scroll-work c d. In the center of the front C' of the dial-box C is a raised circular dial-rim, D, the face of which is ornamented with foliated scroll-work e, and outside of this rim there are in the front C' triangular panels g, ornamented with leaves h i. What I claim is—

The design for the case of a weighing-machine, consisting of the column A, of rectangular horizontal section, having in its front larger and smaller panels, p p', having pilasters B, with ornamental bases a b and capitals c d, the dial-box C, having on its front the dial-rim D, with ornaments e, and triangular panels g, ornamented with leaves h i, and having on its top the entablature with foliated frieze j and foliated cornice k, all arranged and disposed substantially as shown and described.

HANS A. SCHNEEKLOTH.
